UNITED STATES PATENT OFFICE.

PHILIP BOLOUGH, OF NEW YORK, N. Y.

WINDOW CONSTRUCTION.

1,404,085.

Specification of Letters Patent. Patented Jan. 17, 1922.

Application filed October 30, 1920. Serial No. 420,655.

To all whom it may concern:

Be it known that I, PHILIP BOLOUGH, a citizen of the United States, and a resident of the city of New York, borough of Manhattan, in the county and State of New York, have invented a new and Improved Window Construction, of which the following is a full, clear, and exact description.

This invention relates to a window construction, and has for an object to provide a window construction which provides a rigid, compact and efficient window which at all times is waterproof.

Another object resides in the provision of means whereby a pivoted window throughout its entire movement is so constructed as to prevent a leakage of water through the joints of the window.

A further object resides in the provision of the particular construction and arrangement of parts hereinafter described and claimed and shown in the accompanying drawings.

In general my invention comprises a weatherproof structure for windows, with particular reference to windows which are used in series and are pivoted where the ends of adjacent windows overlap each other. It has been found exceedingly difficult to construct windows of this sort that are absolutely waterproof, particularly around the portion of the window where it is pivoted to a stationary beam or stud. I overcome this difficulty by the invention which forms the subject matter of this application in that in any position in which the window may be disposed the joint, particularly around the pivot point, is always watertight, and when the window is closed the entire structure is waterproof.

The invention is shown in the drawings, of which—

Figure 1 is a partial elevation of a series of pivoted, overlapping windows, showing them in their closed position;

Figure 2 is a section taken on the line 2—2 of Figure 1;

Figure 3 is a side view showing one of the windows open;

Figure 4 is a section taken on the line 4—4 of Figure 1; and

Figure 5 is a section taken on the line 5—5 of Figure 1.

Windows constructed in accordance with my invention are adapted to be used in a

vertical or vertically inclined series of overlapping, pivoted windows, such as are adapted for use in roofs or skylight ventilators. Especially in those constructions where the transparent covering is inclined over an aperture in the roof of a building, it is particularly desirable that when these transparent units are closed they be absolutely weatherproof. Accordingly, I have provided in each series a plurality of overlapping windows which are pivoted at the middle of each side portion in vertical or vertically inclined beams and are so disposed that when they are closed the forward end of one window is provided with a depending flange which overlaps the corresponding forwardly extending flange on the window immediately below in the series.

To make the lateral edges of the window tight where they lie and pivot adjacent the edges of the supporting beams, I provide one end of each lateral edge of the window with an overlapping, channellike flange portion adapted to overlap an upstanding edge of the stationary beam, and on the edge of the beam adjacent the rear portion of the lateral edge of the window, I provide a stationary overlapping channel flange portion adapted to receive the rear portion of the lateral edge of the window when the window is closed. Particularly along the adjacent ends of these channel flange portions they are curved and circular in form, the flange portions on the window slipping within the flange portions on the beam and having a common center coincident with the axis of the supporting shaft for the window. The forward portion of the channel flange member on the window is adapted, when the window is closed, to overlap the upper rear edge of the corresponding flange portion on the beam immediately below the end of this window, so that the whole unit when closed is weatherproof.

Each unit is comprised as follows: A frame, preferably made of sheet metal, designated by the numeral 1 is adapted to receive transparent units 2. Each frame along its forward edge 3 is provided with a depending flange portion 4 adapted to overlap, when in its closed position, an upwardly extending flange portion 5 on the rear upper end of the window immediately below. Each window frame is supported along its lateral edges on bolts or shafts 6 suitably

supported in **T** beams 7. This **T** beam is inverted, as shown in Figure 5, and the ends of shafts 6 are supported in plates 8 and 9. These plates and the **T** beams 7 form part 5 of a bar or stud which is preferably made of sheet metal 10 and provided with up-standing rib portions 11 along the upper lateral edges to provide a channel along the upper face of the beam down which the 10 water may flow.

Made integral with or suitably fastened thereto in any desired manner along the forward portion of each lateral edge of the frame 1 is an upturned, overlapping 15 channel flange portion 12 which is adapted to extend over the adjacent rib 11 on the supporting beam. This channel flange portion 12 at its end adjacent the middle portion of each frame is formed circular in 20 shape, as designated by the numeral 13, and is cut away in a suitable portion 14 so as to permit the window to have the required pivoted movement around the shaft 6. The rear of each lateral edge of the frame 1 is 25 not provided with an overlapping flange portion, but in order to make this part of the window frame weatherproof, the adjacent edge of the supporting beam is provided with a fixed stationary overlapping 30 channel portion 15 which is adapted to receive the rear portion of each lateral edge of the frame 1 when the window is closed, as shown in Figure 2. The end of this general flange portion 15 adjacent the middle of the 35 window section is curved circular in form, as designated by the numeral 17, and overlaps the above-mentioned curved flange portion 13 on the window frame. The angular extension of the curved flange portions 13 40 and 17 are so designed that they overlap each other sufficiently when the window frame is closed to prevent the water from getting through, and seal the lateral edges of the window tight. The upper rear end 18 of the 45 channel portion 15 extends far enough up on the edge of the supporting beam to be overlapped by the front lower end of the channel flange portion 12 of the window next in order above in the series.

50 Any suitable operating means can be used to actuate these windows separately or as a unit, but preferably I use the actuating means which is the subject matter of my copending application, Serial No. 363541, 55 skylight ventilator, filed March 5, 1920.

It will thus be observed on consideration of the above description that I have provided a window construction whereby a plurality of window frames can be pivotally 60 mounted between beams and operated as a unit and which when in closed position present an absolutely weatherproof barrier between the elements and the interior. The various parts of this construction can be made 65 of any suitable material, but is preferably

made of sheet metal; and minor modifications can be made in this structure without departing from the spirit of the invention.

What I claim is:

1. A window construction comprising a 70 window frame having lateral edges, a supporting beam on which the window frame is pivoted having an edge adjacent the lateral edge of the window frame, the edges of the beam rising above the top surface thereof 75 to form a channel, a flange on the forward lateral edge of the window adapted to overlap the adjacent edge of the beam, and a flange on the edge of the beam adapted to overlap the rear portion of the lateral edge 80 of the window.

2. A window construction comprising a supporting beam, a window frame pivoted thereto, a plurality of flanges disposed on the adjacent edges of the beam and the 85 window frame adapted to overlap each other to render the structure weatherproof when the window is closed, and a depending flange on the forward lower edge of the window frame adapted to overlap the edge of the 90 adjacent window.

3. A window construction comprising a supporting beam, a window frame pivoted thereto, said window frame having lateral, front and rear edges, a channel flange on 95 the forward portion of each lateral edge adapted to overlap an edge of the beam, a channel flange on the edge of the beam adapted to overlap the rear portion of the lateral edge of the frame, and a depending 100 flange on the forward edge of the frame adapted to overlap the rear edge of an adjacent window when the window is closed.

4. A window construction comprising a supporting beam, a window frame pivoted 105 thereto, a channel flange on the lateral edge of the frame adapted to overlap an edge of the beam, and a channel flange on the edge of the beam adapted to overlap the lateral edge of the window frame, the adjacent portions of these flanges being curved 110 in form, the curved portion of the flange on the beam adapted to overlap and embrace the curved portion of the flange on the frame.

5. A window construction comprising a supporting beam, a window frame pivoted thereto, a channel flange on the lateral edge of the frame adapted to overlap an edge of the beam, and a channel flange on the 120 edge of the beam adapted to overlap the lateral edge of the window frame, the adjacent portions of these flanges being curved in form, the curved portion of the flange on the beam adapted to overlap and embrace 125 the curved portion of the flange on the frame, the pivot point of the window frame being the center of each of said curved channel flange portions.

PHILIP BOLOGH.
